UNITED STATES PATENT OFFICE.

WILLIAM F. STONE, OF WOODBURY, NEW JERSEY, ASSIGNOR TO STAR SEAL COMPANY, OF NEW YORK, N. Y., A CORPORATION OF NEW YORK.

MACHINE FOR PACKAGING LIQUIDS.

1,173,148.

Specification of Letters Patent. Patented Feb. 22, 1916.

Application filed January 17, 1913. Serial No. 742,721.

To all whom it may concern:

Be it known that I, WILLIAM F. STONE, a citizen of the United States, residing at Woodbury, in the county of Gloucester and 5 the State of New Jersey, have invented certain new and useful Improvements in Machines for Packaging Liquids, of which the following is a specification.

This invention relates to machines for 10 packaging liquids, and particularly to a combined bottle filling and capping machine especially designed to fill such bottles as are used to contain soft drinks and the like where syrup and charged water are 15 forced into the bottle and the bottle then capped.

My present invention contemplates the filling of a bottle with syrup and charged water from a single delivery nozzle and 20 at a single clamping.

The present machine has proved to be not only a time saver, but can handle the syrup more effectively in conjunction with the charged water which keeps the passages 25 flushed out and free. Furthermore, in machines of this class it has been desired that the sniffer valve employed in exhausting the expanded gases backed up in the bottle neck be operated in combination with 30 a reverse movement of the handle to insure that the charged liquid will be first shut off before the sniffer valve is opened. To the end, therefore, of providing means for filling a bottle with syrup and water from 35 a single nozzle and at a single clamping, and for operating the sniffer valve in combination with a reverse movement of the handle, to first shut off the charged liquid before said sniffer is opened, I have devised 40 my present invention.

In this invention I mount a filling head for movement on a suitable support and extend a capping plunger into said head. The head has a plural liquid supply including a syrup pump and a charged water valve and the arrangement is such that the charged water is delivered subsequent to the delivery of the syrup so that the delivery passages are properly flushed out. The 45 delivery of both syrup and charged water is through a single clamping nozzle and is effected at a single clamping operation. A sniffer device is associated with the head and may be operated at any time to exhaust such gases as may have formed in 50

the bottle. The various operating elements of the machine are successively brought into operation by an operating mechanism having a plurality of successively active phases including a head lowering phase, a bottle 60 neck clamping phase, a pump actuating phase, and a charged water discharge phase in one direction, and having a sniffing phase, a bottle sealing phase, a bottle unclamping phase, and a head raising phase 65 in the opposite direction.

The construction and operation of my improvements will be more fully pointed out in the specification which follows, and as illustrative of the invention I have shown 70 in the accompanying drawings an embodiment which I have found practical and well adapted for the purposes intended.

Throughout specification and drawings similar characters of reference will denote 75 corresponding parts.

Figure 1 is a vertical, sectional view through a machine constructed in accordance with my invention. Fig. 2 is a perspective view of the upper part of my machine. Fig. 3 is a transverse section on the line 3—3 of Fig. 1. Fig. 4 is a vertical section on the line 4—4 of Fig. 3. Fig. 5 is a detail view of the bottle clamping means. Fig. 6 is a view of such of the parts 80 as would be exposed along the line 6—6 of Fig. 3, with handle elevated. Fig. 7 is a similar view illustrating the positions of these parts with handle fully depressed. Fig. 8 is a view illustrating the parts in 85 their movement intermediate of the points shown in Figs. 6 and 7. Fig. 9 is a perspective view of the movable head of the machine. Figs. 10 and 11 are detail views of cams used in the operation of the machine. Fig. 12 is a fragmentary section of 90 a bottle neck illustrating the position of the cap and plunger before the bottle is sealed, and Fig. 13 is a similar view with the cap applied to the bottle.

The numeral 1 designates a suitable supporting frame in which is fulcrumed a treadle lever 2 to the inner end of which is pivoted a vertically movable rod 3. A clamping collar 4 is fixed upon said rod and 95 supports a bottle seat 5 upon which is seated a bottle 6 retained in position by a guide 7 secured to the frame. Upon the upper part of the frame is mounted a movable head 8, in which fits a vertical plunger 9. The head 100

8 is formed at its lower end with a depending flange 8¹ providing an annular recess in which is seated a compressible rubber ring 8². This ring fits around the lower end of 5 the follower 9 and has a slightly flaring tubular extension 8³ into which the neck of the bottle is adapted to be thrust and capped by a cap 11 detachably retained by a cap holding ring 11¹ fitted on the lower end of 10 the follower. The flange 8¹ has a screw threaded connection with a collar 10 provided with a pair of ears 47 to which is pivoted a pair of links 46 whose lower ends project under the lower end of the flange 8¹ 15 and bear against the flaring tubular portion 8³ of the compressible ring 8². These links 46 are effective when expanded to compress the rubber ring and cause it to tightly clamp the neck of the bottle, thus providing 20 a water tight joint to prevent escape of the fluids. The manner in which this expansion of the links is accomplished will be more particularly pointed out hereinafter. The other end of the follower passes through 25 a sleeve 12 integral on the frame, and has a yielding bearing in the form of a spring 13 surrounding its upper end and confined within said sleeve.

A syrup pump 14 is mounted on the frame 30 and receives syrup from a suitable connection 15, controlled by a suitable check valve 15¹ and discharging into a syrup chamber 16, controlled by a spring actuated valve 17, seated in a valve casing 18, and communicating with the filling nozzle by means of a conduit 19. The charged water is admitted into a container 20, communicating with the conduit 19 and supplied from a suitable source. Said casing is controlled by the 35 valve 21. The "sniffer" or vent valve 22 is oppositely mounted, and has a connection 23 to convey the exhausted gases into the atmosphere. The syrup and charged water thus enter the bottle through a single nozzle 40 and at a single clamping. This construction effects a saving of time, as well as keeping the passage flushed out and free from the gumming action of the syrup.

Journalized transversely of the frame is a 45 spindle 24 to one end of which is fastened a plate 25 which provides a support for a pivoted clamp operating lever 42. A crank disk 27 and a crank 28 on the handle 29 are employed to rotate said spindle. Fast on 50 said spindle is a cam 30, formed with a cam slot 31, terminating at one end in recesses or pockets 32, in which are normally engaged the rolls 33 on the upper end of the link 34, the lower end of which link is pivoted to a block 35 fast on the rod 3 and supported on the transverse web 36, of the frame 1.

Fastened to the cam 30 is one end of a 55 valve actuating arm 37, formed with an inclined portion or cam shoulder 38, upon its

long arm, and having its free end bent downwardly at substantially right angles and terminating in a second cam shoulder 39, the purpose of which shoulders being to successively operate the charged water 70 and "sniffer" valves. A second cam 40 is fastened to the cam 30, and is engaged by the roll 41 on one end of the clamp operating lever 42, pivoted centrally to the plate 75 of the spindle, and bifurcated at its opposite end to work over a guide pin 43 on the collar 44 of the movable head. This collar 44 is formed with wedges 45 effective when the collar is moved, to engage the rolls 45¹ carried by the upper ends of the links 46, 80 thus expanding said links to cause the lower ends thereof, which are pivoted in the ears 47 of the split collar 10, to contract the compressible ring 8² about the neck of a bottle.

The pump is reciprocated by means of a 85 link 48, eccentrically fastened to the crank disk 27 of the spindle at its lower end and slotted at its upper end. In this slot 49 a stop 50 is located. One end of a detachable coupling head 51 works in said slot, the other end of which head is detachably mounted on the pump rod 52 of the syrup pump 14. The pump rod is guided and steadied by the angle bracket 53 fastened to the sleeve 12.

The operation is as follows—Assuming the parts to be in the position shown in Fig. 9 with the crank arm 28 raised, the link 34 will be seen to be supporting or propping up the movable head. This position is illustrated in Fig. 6. When the handle is moved downwardly the spindle 24 is rotated, thus moving the arm 37, cams 30 and 40, and clamp operating lever 42. The link 34 swings to the right, as shown in Fig. 8, in 105 which figure the parts are in their intermediate positions. This movement of the link causes the cam 30 to which is fastened the cam 40, to swing toward the right, thereby moving the arm 37 from its normal 110 position at the right in a direction toward the left as shown in Figs. 6, 7 and 8. This movement of the arm 37, however, is retarded by reason of the engagement of the rolls 33 on the upper end of the link 34 115 with the recesses 32 in one end of the cam slot 31 of the cam 30. The cam slot and recesses thus act in the nature of an idler slot to retain the arm 37 until such a time as the pump has pumped a charge of syrup 120 into the bottle. The rotation of the spindle 24 and cams tends to rock the clamp operating lever 42 by reason of the engagement of the roll 41 on one end of said lever with the cam 40. Inasmuch as the other end of 125 said lever is fitted upon the pin 43 of the collar 44, the said collar is moved downwardly. This downward movement of the collar 44 causes the wedges thereon to expand the upper ends of the links 46, the 130

130

lower ends of which are pivoted in the ears formed on the collar 10 thus contracting the lower ends of said links and clamping the compressible rings 82 about the neck of the bottle. In the mean time, the link 48 has been actuated by the rotation of the crank disk 27 to which it is fastened to reciprocate the piston rod 52 of the syrup pump, thus pumping a charge of syrup into the bottle. Just at the time when the pump rod has completed its stroke, the valve operating arm 37 has completed its swing and occupies the position shown in Fig. 7. The rolls 33 on the link 31 now have been disengaged completely from the recesses 32 of the cam 30, both cams have reached their utmost movement to the right, the rolls are at the extreme left end of the cam slot, and the clamp operating lever 42 has been rocked to tighten the ring 82 on the bottle neck. With the parts in this position and the charge of syrup pumped into the bottle, the projection 38 on the valve operating arm 37 will strike against the valve controlling the supply of charged water to the bottle to admit a proper amount. The reverse movement of said arm 37 will cause the other projection 39 to open the "sniffer" valve to permit the escape of the backed up gases in the bottle, which gases prevent bottle being completely filled. When the bottle has been "sniffed", the operating arm 37 is again brought forward until projection 38 operates valve 21 allowing bottle to fill. In this position and with full gas pressure on bottle contents, the bottle is ready to be capped. The capping is performed by depressing the treadle 2, thereby lifting the rod 3 and moving the bottle into contact with the cap seated in the cap holding ring of the yieldingly mounted follower. The upward movement of the bottle seats the cap thereon, whereupon the treadle is released and the rod 3 and bottle are lowered. The valve actuating member 37 is now returned to its normal position, and the filled and capped bottle may then be removed from its seat and an empty one substituted.

Various modifications in the arrangement and construction of the parts may be resorted to whenever found necessary if falling within the spirit and scope of the invention as defined in the appended claims.

What I therefore claim and desire to secure by Letters Patent is:—

1. In a bottle filling machine, a movable filling head including a syrup pump, a control for charged water, and a gas exhausting device, and a multi-phase operating mechanism for said filling head including means effective upon movement of said mechanism in one direction to first actuate said pump, means subsequently effective to actuate said charged water control, and means finally effective upon a movement of

the operating mechanism in the opposite direction to actuate said gas exhausting device.

2. In a filling machine, a syrup controlling valve, a charged water controlling valve, and a "sniffer" or gas exhausting valve, and a member arranged for successive contact with said charged water and "sniffer" valves, and means to bring to operative position said contact member subsequent to the operation of the syrup control valve whereby said charged water valve will be first operated and the reverse movement of said contact member will operate the "sniffer" valve. 30

3. In a bottle filling machine, a movable filling head including a plural liquid supply and a gas exhausting device operatively associated therewith, and an operating mechanism for said filling head including means effective upon a movement of the operating mechanism in one direction to actuate one element of said plural liquid supply, means effective upon a further movement of said mechanism to actuate another element of 90 said plural liquid supply, and means effective upon a movement of said mechanism in the opposite direction to actuate said gas exhausting device. 85

4. In a machine of the class described, a syrup pump, a charged water valve, and a "sniffer" or gas exhausting valve opposite said charged water valve, a rotatable spindle, a pair of cams thereon, a valve actuating device on one of said cams, means operated by the rotation of the spindle effective to operate said syrup pump, and a pair of members on said valve actuating device to successively operate said charged water and "sniffer" valves subsequent to the operation of the syrup pump. 100

5. In a machine of the class described, a syrup pump, a charged water valve, and a "sniffer" valve, a rotatable spindle, a pair of cams fastened to each other and mounted 110 on the spindle, a valve actuating device mounted on one of said cams, a clamp operating lever pivotally mounted and positioned for movement by the other of said cams, a movable collar operatively disposed 115 relative to said clamp operating lever, a clamping collar adapted for engagement with a bottle neck and operatively connected with said movable collar, and a pair of projections on the valve actuating device to 120 successively operate the charged water and "sniffer" valves, the movement of said spindle being effective through operative connections to first operate the syrup pump. 125

6. In a machine of the class described, a syrup pump, a charged water valve and a "sniffer" or gas exhausting valve, a rotatable spindle, a pair of cams fastened to each other and mounted on the spindle, a valve actuating device mounted on one of 130

said cams, a clamp operating lever pivotally mounted and positioned for movement by the other of said cams, a movable collar operatively disposed relative to said clamp 5 operating lever, a clamping collar adapted for engagement with a bottle neck, a pair of links on said clamping collar, a pair of wedges on the movable collar to expand said links, and a pair of projections on the valve 10 actuating device to successively operate the charged water and "sniffer" valves, the movement of said spindle being effective through operative connections to first operate the syrup pump.

15 7. In a bottle filling machine, a bottle support, a movable filling head, a plural liquid supply and a gas exhausting device associated with said head, and an operating mechanism for said head having a plurality 20 of successively acting phases in one direction and including means for lowering said head, means for clamping a bottle neck, means for effecting discharge of one element of said plural supply, and means for effecting discharge of another element of said plural supply, said mechanism having means effective upon movement of the operating mechanism in the opposite direction to actuate the gas exhausting device, the 25 continued movement of said mechanism in said direction successively unclamping the bottle neck and raising the head to permit removal of the bottle from the support.

8. In a machine of the class described, a charged water and a syrup supply, a control valve for each liquid, a single delivery nozzle for both liquids, a valve to exhaust the gases released in the bottle, and a device mounted for swinging movement relative to said valves and having a cam shoulder effective to operate the charged water valve and having a second shoulder effective upon the reverse movement of the device to operate the exhaust valve.

45 9. In a bottle filling machine, a filling mechanism including a plural liquid supply having a single delivery nozzle, a gas exhausting device operatively associated with said plural supply, an actuating device having means effective upon a movement thereof in one direction to operate one of said elements of the plural supply, and means operatively associated with said actuating device and effective upon a movement of the actuating device in the opposite direction to actuate said gas exhausting device.

10. In a bottle filling machine, a movable filling head including a plural liquid supply and a gas exhausting device operatively associated therewith, and an operating mechanism for said head including means effective upon a movement of the operating mechanism in one direction to actuate one element of said plural supply, means effective upon a further movement of said mech-

anism in the same direction to actuate another element of said plural supply, and means effective upon a movement of the operating mechanism in the opposite direction and prior to the return of said mechanism 70 to initial position to actuate the gas exhausting device.

11. In a machine of the class described, a syrup pump, a charged water delivery, and a gas exhausting device, an operating mechanism for said pump, means effective upon a movement of said pump operating mechanism in one direction to actuate said charged water delivery, and means effective upon the return movement of the pump operating mechanism to its initial position and prior to said mechanism reaching its initial position to actuate said gas exhausting device.

12. In a machine of the class described, a filling mechanism including a compressible clamping member adapted for engagement about the mouth of a receptacle, a member movably mounted relative to said clamping member, a pressure exerting device pivoted 85 between its ends and having one end disposed for compressive engagement with said clamping member, means effectively disposed to act upon the other end of said pressure device upon actuation of said movably 90 mounted member to force said first named end into engagement with said clamping member, and means for actuating said movable member.

13. In a filling mechanism, a head, a movable member carried thereby, a compressible clamping member carried by said head, a pressure exerting device pivoted between its ends to said head and having an end disposed for compressive engagement with said 105 clamping member and having its opposite end disposed for engagement with said movable member.

14. In a filling mechanism, a head, a member carried thereby and having a cam surface, a compressible clamping member carried by said head, a pressure exerting device pivoted between its ends to said head and having an end disposed for compressive engagement with said clamping member and 110 having a roll at its opposite end disposed for engagement with said cam surface.

15. In a bottle filling and capping machine, a frame, a sliding element guided therein, a filling head movably mounted on 120 said slide, a capping plunger extending into said head, a bottle support on said frame mounted on said slide, an operating mechanism having a plurality of successively active phases and including means for lowering said head and means for filling a bottle and means for moving said slide relatively to said capping plunger.

16. In a machine of the class described, a filling mechanism having a compressible 130

clamping member, a member movably mounted relative thereto, a pair of radially effective pressure exerting devices effectively disposed relative to said clamping member, 5 means effective upon a movement of said movable member to cause said radially effective members to contract said clamping member about a bottle neck, and means for actuating said movable member.

10 17. In a machine of the class described, a filling mechanism including a compressible clamping member, a member slidably mounted relative thereto, a pair of pressure exerting devices pivoted between their ends 15 and effectively disposed in oppositely acting relation to each other and in contracting relation to said clamping member, means operated by said slidable member and engaging the free ends of said pressure devices for 20 causing movement of their engaging ends toward each other whereby to contract said clamping member about a bottle neck upon an effective actuation of said slidable member, and means for actuating said slidable 25 member.

18. In a bottle filling machine, a supporting frame, a filling head movably mounted thereon, a syrup pump carried thereby, operating mechanism for raising and lowering 30 said head and for operating said pump including a lost motion connection disposed in operative relation for the lowering of the head in one direction prior to pumping and for raising the head in the other direction 35 during the intake of the pump.

19. In a machine of the class described, a charged water valve and a gas exhausting device, and a single actuating member pivotally disposed for swinging movement past 40 said valve and device, means on said member for actuating said charged water valve, and means on said member independent of said first named means for actuating said gas exhausting device.

45 20. In a machine of the class described, a charged water valve and a sniffer valve, a single actuating member disposed for swinging movement between said valves, means on said member for actuating said charged 50 water valve in one direction of movement of said member, and means on said member for actuating said sniffer valve on the return movement of said actuating member.

21. In a machine of the class described, a charged water valve and a sniffer valve arranged oppositely thereto, an actuating member arranged for swinging movement between said valves, a device on said member arranged to actuate said charged water 60 valve in one direction of movement of said member, and oppositely set means associated with said actuating member and arranged to actuate said sniffer valve on the return movement of said actuating member.

65 22. In a machine of the class described, a

frame, a sliding element, a filling head movably mounted thereon, a bottle support fixed on said sliding element, a capping plunger on said frame and extending into said head, means for moving said head relative to said support and means for moving said sliding element relative to said plunger.

23. In a bottle filling machine, a frame, a filling head movably mounted thereon and including a pump and a charged water valve and a sniffer valve, a support fixed on said frame, an operating mechanism for said pump and charged water and sniffer valves having a plurality of successively active phases one of which is effective to actuate said pump, said operating mechanism including a flexible connection between said head and said support including a pair of relatively slidable members and a valve operating device fast on one of said members 80 and effectively disposed to successively actuate both of said valves subsequent to the effective pump actuating phase.

24. In a bottle filling machine, a frame, a filling head movably mounted thereon and including a pump and a charged water valve and a sniffer valve, a support fixed on said frame, a multi-phase operating mechanism for said pump and charged water and sniffer valves effective to successively actuate the pump, charged water valve and sniffer valve, said operating mechanism including a flexible connection between said head and support including a pair of relatively sliding members, one of 90 said members having a slot therein terminating in pockets at one end, means on the flexible connection normally engaged in said pockets, and a valve operating device 95 operatively connected with one of said members and effectively disposed to successively actuate the charged water and sniffer valves subsequent to the effective pump actuating phase.

25. In a bottle filling machine, a frame, a filling head movably mounted thereon and including a pump and a charged water valve and a sniffer valve, a support fixed on said frame, a multi-phase operating mechanism for said pump and charged 110 water and sniffer valves effective to successively actuate the pump, charged water valve and sniffer valve, said operating mechanism including a pivotal connection 115 between said head and support, including a pair of relatively slidable members, one of said members having a slot therein in which one end of the pivotal connection is engaged, a valve operating device fast on one of said members and having engaging 120 portions effectively disposed to successively actuate the charged water valve and sniffer valve subsequent to the effective pump actuating phase.

26. In a bottle filling machine, a frame, a

filling head movably mounted thereon and including a syrup pump and a charged water valve and a sniffer valve, a multi-phase operating mechanism for said elements including a fixed member on the frame, a rotatable element, an operating link pivotally connected to said fixed member and having a slidable engagement with the rotatable element of the head, said engagement including means for varying the effective length of said link up to a predetermined position, said slidable engagement being ineffective during the remainder of said rotatable movement, and a valve operating device operatively connected with one of said relatively movable members and effectively disposed to successively actuate said charge water and sniffer valves subsequent to the effective pump actuating phase.

27. In a bottle filling machine, a frame, a member fixed thereon, a filling head movably mounted relatively to said member and including a pump, a charged water valve and a sniffer valve, one of said relatively movable members including a rotatable ele-

ment, a supporting link pivotally connected to one of said members and having a slidable engagement with the rotatable element of the other member, said engagement including means for varying the effective length of said link up to a predetermined position, said slidable engagement being ineffective during the remainder of said rotatable movement, an independent operating device on said rotatable element and an operable device disposed in the path of said independent operating device and engageable thereby during that time when the link is non-effective with respect to the rotatable element, the effective movement of said independent operating device successively actuating the charged water and sniffer valves.

In testimony whereof I affix my signature in presence of two witnesses.

WILLIAM F. STONE.
